BAROMETER

Knute Heinz, Pearl River, N.Y., assignor to The Curtis Publishing Company, Philadelphia, Pa., a corporation of Pennsylvania

Filed June 1, 1964, Ser. No. 80,215

Term of patent 14 years

(Cl. D52—7)

FIG. 1 is a front elevational view of a barometer showing my new design;

FIG. 2 is a top plan view thereof;

FIG. 3 is a left-side elevational view thereof;

FIG. 4 is a rear elevational view thereof; and

FIG. 5 is a right-side elevational view thereof.

I claim:

The ornamental design for a barometer, as shown.
